IRONING MACHINE

Edward C. Peter, Algonquin, and John A. Castricone, Elgin, Ill.; said Peter assignor to The American Ironing Machine Company, Algonquin, Ill., a Corporation of Illinois

Application March 28, 1931. Serial No. 525,996

4 Claims. (Cl. 68—9)

This invention relates to that class of ironing machines having a rotary ironing roll and an ironing shoe mounted in movable relation to each other and having means for effecting and controlling the operations of the ironing roll and shoe relatively to each other.

The principal object of the invention is to provide an improved power-driven ironing machine having a rotative ironing roll and an ironing shoe mounted in movable relation to each other, with improved simple and efficient means for automatically controlling the rotation of the ironing roll and for controlling the operations of the ironing shoe or bodily movable member in coordinated relation to each other.

A further object of the invention is to provide ironing roll and ironing shoe operating and controlling means comprising a rotative eccentric mounted on or adapted to revolve around the axle of the ironing roll and operatively connected with the ironing shoe for moving the same toward and from the ironing roll, and means for automatically controlling the operation of said eccentric or shoe operating means and ironing shoe relatively to the rotation of the ironing roll and the stopping and starting of the same, said controlling means including manually operable escapement mechanism or pawl and ratchet and tripping mechanism for connecting the ironing roll and ironing shoe with a source of power or power-driven shaft and gear mechanism and means for releasing said connection.

A further object of the invention is to provide an ironing machine having a rotative ironing roll and an ironing shoe mounted in movable relation to each other, and improved means for operatively connecting said ironing roll and ironing shoe with a source of power for operating the same including simple and efficient means for stopping and starting the rotative movement of the ironing roll and the movements of the ironing shoe toward and from the ironing roll in predetermined coordinated relation and in such a manner that the ironing roll is connected with the driving mechanism and released from the same while the pressure of the ironing shoe toward the ironing roll is released so as to facilitate the operation of the connecting and releasing means.

A further object of the invention is to provide an improved ironing machine having a rotative ironing roll and an ironing shoe mounted in movable relation to each other and having driving gear mechanism adapted to be connected with a source of power for operating said roll

and shoe, with improved simple and efficient means for rotating and stopping the ironing roll, and means operatively connected with and adapted to be operated in coordinated relation to the operations of the ironing roll to effect the operation of the ironing shoe toward and from the ironing roll in coordinated relation to the stopping and starting of the roll, including means for automatically releasing the ironing shoe from the driving mechanism without stopping the rotation of the roll, and means for releasing the ironing roll from the driving mechanism either manually or automatically.

Other and further objects of the invention will appear from the following description and claims and from an inspection of the accompanying drawings, which are made a part hereof.

The invention consists of the features, combinations, details of construction and arrangement and mode of operation of the parts as herein described and claimed.

In the accompanying drawings—

Figure 1 is a view in end elevation of an improved mechanism for operating the ironing roll and shoe of an ironing machine constructed in accordance with our invention with the front wall or end plate of the machine frame or head which forms the gear casing removed;

Fig. 2 is a plan view of the mechanism shown in Fig. 1, with the top of the casing or housing and part of the ironing roll and the ironing shoe broken away or omitted;

Fig. 3 is a view in transverse vertical section taken on line 3—3 of Fig. 2 looking in the direction indicated by the arrows, and showing the escapement or pawl and ratchet and tripping mechanism for controlling or stopping and starting the rotation of the ironing roll and the movements of the ironing shoe toward and from the ironing roll;

Fig. 4 is a view in vertical sectional elevation taken on line 4—4 of Fig. 2, looking in the direction indicated by the arrows, and showing the power-actuated main driving shaft and worm and worm-wheel mechanism for driving the ironing roll, and the clutch and connecting and releasing mechanism for connecting the ironing roll with the driving mechanism, and showing the rocking-shaft and lever mechanism for supporting and operating the ironing shoe with parts omitted for clearness of illustration;

Fig. 5 is a view in longitudinal central sectional elevation taken through the longitudinal center of the ironing roll and roll-operating mechanism, and through the center of the iron-

ing shoe supporting and operating rocking shaft, on irregular line 5—5 of Fig. 1, looking in the direction indicated by the arrows;

Fig. 6 is a view in rear elevation of the ironing machine shown in Figs. 1 to 5 inclusive, with parts of the pedestal and base or supporting frame omitted; and

Fig. 7 is a detail view of the escapement or pawl and ratchet mechanism shown in Figs. 3 and 4, as the same would appear when seen from the rear.

In constructing an improved ironing machine in accordance with our invention, a machine frame 1 is provided which comprises a head or housing 2 which is adapted to be supported upon a supporting table 3, or upon a pedestal or supporting base 4. Either a base adapted to be supported upon a table or other suitable support, or a pedestal adapted to support the main frame or housing 2 and the working parts of the machine independently of a table or similar support may be employed. Such bases and pedestals are in common use and well-known and it is therefore deemed unnecessary to further describe or illustrate the same in detail herein.

The head or housing 2 is provided with a main bearing 5 which projects horizontally from the inner end wall 6 of the housing 2 and is adapted to form a strong and substantial supporting bearing for a rotative ironing roll and its supporting axle. A preferably hollow ironing roll 7 is provided having an end head 8 at the inner end thereof adjacent to the bearing 5 and main frame or housing 2, and having a similar end head 9 fixed within the outer extremity of the hollow cylindrical wall of said roll. A stationary hollow shaft or tubular ironing roll-supporting member 10 is by preference rigidly supported in the bearing 5 and extends longitudinally within the cylindrical hollow ironing roll 7 and through the end heads 8 and 9 which are provided with flanged axial openings 11 and 12 through said heads. Annular bushings or bearing sleeves 8' and 9' are mounted in said openings 11 and 12 in the ironing roll head and encircle the said stationary hollow shaft or tube 10 and are adapted to rotate around the same. The said stationary hollow shaft or tube is thus adapted to rotatively support said ironing roll which is journaled thereon. The inner end 13 of the hollow shaft or tube 10 extends inward through the projecting bearing 5 and into the gear chamber 14 formed by said head or housing 2.

An inner rotative axle-shaft or central axial member 15 is mounted centrally within said stationary hollow shaft or tubular ironing roll supporting member 10 and has its outer end 16 fixed to the outer end head 9 of the hollow ironing roll 7 by suitable connecting means which may be of any ordinary and well-known or suitable form.

For example, an inner end bushing 17 having a central axial opening 18 therethrough is mounted upon said outer end 16 of the inner rotative axle shaft 15 and secured in rigid relation to said axle shaft and to the end head 9 of the ironing roll by means of a transverse tapered securing-pin 19 which extends through aligned transverse openings in said inner bushing 17 and inner axle-shaft 15. The bushing fits into and in rotative relation to the open end of the stationary tubular axle member 10, which is surrounded by the bearing sleeves or rings 8' and 9' as already described. A transverse securing bar

21 is secured in fixed relation to the outer end of the inner axle shaft 15 by means of a headed securing screw 22. And said securing bar 21 extends through a transverse opening 23 in a perforated or slotted projecting lug 24 on said inner bushing 17, the projecting end of said securing bar 21 being releasably secured in fixed relation to the end head 9 of the ironing roll by means of an inwardly projecting securing-pin 25 on said bar, said pin being adapted to extend into a suitable opening 26 in the said ironing roll head 9. The outer ends of the ironing roll 7 and inner axle-shaft 15 are thus rigidly connected and said rotative inner axle-shaft 15 is adapted to rotate with the ironing roll and to serve as a means for rotating and controlling the operations of said roll. The inner end 30 of said inner rotative axle shaft 15 projects beyond the inner end of the stationary hollow tube or shaft 10 and into the gear chamber 14 formed by the housing 2.

An inner resilient packing ring or sleeve 27 surrounds the outer end of the axle rod 15 within the stationary tubular roll-supporting member 10 preventing the escaping of oil. The inner extremity of the inner axle-shaft 15 projects endwise beyond the inner extremity of said tubular ironing roll supporting member 10 and into or through the gear chamber 14 and is journaled in an upright inner supporting frame member or bracket 28 which is located in said gear casting and provided with an annular metallic bearing ring or bushing 29 adapted to encircle and rotatively support said projecting extremity of said axle-shaft in operative position and in position to be operatively connected with suitable mechanism for driving and controlling the rotation and operation of said ironing roll and its rotative axle-shaft or spindle 15.

An electrically heated ironing shoe 31, which may be of any ordinary and well-known or suitable form, having a concave ironing surface facing toward the peripheral surface of the ironing roll 7, is reciprocally mounted adjacent to and back of said ironing roll and movable toward and from the same for effecting the ironing of material to be operated upon as such material is fed between the upper and peripheral surface of the ironing roll and the inner concave face of said ironing shoe by the operator in the usual manner. Suitable rocking shoe-supporting and operating shaft and lever mechanism is provided which comprises rock shaft and lever mechanism for reciprocating or moving said ironing shoe toward and from the said roll in coordinated relation to the operation of the same, and means for controlling and actuating the rotative ironing roll and the operation of said ironing shoe in predetermined coordinated relation, as follows.

A hollow horizontal rock-shaft 32 is rockingly mounted within and extends longitudinally from end to end of a stationary horizontal tubular shoe-supporting arm or hollow shaft 33 which is rigidly mounted in a horizontal tubular supporting frame portion 34 which extends into the lower portion of the gear chamber 14 formed by the head or housing 2 already described, as shown in Fig. 5. Said tubular frame portion 34 is by preference cast in one integral piece with the housing 2 which forms the gear casing, and is provided with an upwardly projecting inner frame portion 35 to which the inner frame or bracket member 28, already described, is rigidly secured by means of securing screws 36.

and 37 as shown in Figs. 1 and 5. The outer extremity of said hollow rock-shaft 32 projects endwise through the adjacent outer open end of said stationary tubular shoe-supporting member 33; and a rocking lever 37 is fixed to said outer projecting end portion of said rock-shaft and extends upwardly therefrom directly back of the longitudinal center of the ironing-shoe 31. The upper end of said rocking lever 37 is flexibly connected with said ironing shoe by suitable connecting means which may be of any ordinary well-known or suitable form. For example, a bracket 38 fixed to the back of the ironing shoe, and a horizontal connecting pin 39 extends through a suitable opening in the upper end of said rocking lever 37 and through suitable openings in the side arm portions 40 of said bracket 38 in which the opposite ends of said pin are anchored. In the form of the device shown in the drawings a helical spring 41 encircles said connecting pin and is provided with a projecting portion 42 which engages the bracket 38, the opposite end 43 being in abutting engagement with the lever 37. The ironing shoe 31 is thus flexibly connected with and supported upon the upper end of the rocking lever 37 and adapted to be moved into and out of yielding engagement with the ironing-roll as the rock-shaft 32 and lever 37 are rocked or reciprocated in the operation of the ironing shoe. An inner end bushing 44 having a threaded central axial opening 45 and a transverse opening 46 therethrough is mounted within the outer end of the hollow rock-shaft 32; and a transverse securing pin 47 is inserted through said transverse opening 46 and through corresponding adjacent openings in the enlarged lower end or head of the rocking lever 37 which surrounds and is thus secured in rigid relation to said hollow rock-shaft. The inner collars or gaskets 49 and 50 are interposed between the hollow rock-shaft 32 and the rigid stationary outer tubular member 33 and tubular frame portion 34 respectively, in which the rock-shaft is rockingly mounted. (See Fig. 5).

The rock-shaft 32 is provided at its opposite or inner end 51 which projects beyond the tubular frame portion 34 within the gear chamber 14 as already described, with a pair of shoe-actuating rocking levers 52 and 53, one of which is fixed to said hollow rock-shaft 32 and the other of which levers is flexibly connected with said rock-shaft and with said fixed lever.

For example, the relatively short fixed lever 52 which by preference comprises in its construction a pair of flat parallel or forked side portions 54 having elongated perforations 55 in their lower extremities through which the projecting end of the rock-shaft extends, is secured in fixed relation to said rock-shaft by means of a sleeve-shaped hub or sleeve 56 which encircles said rock-shaft and is rigidly secured thereto by means of a transverse tapered securing pin 57 as best shown in Fig. 5. The said hub 56 is provided with circumferential end shoulders 58 and 59, the outer shoulder portion 59 being flattened and adapted to engage the flat margins of the elongated openings 55 in said fixed lever 52 so as to securely hold the same in rigid fixed relation to the said hub or sleeve and to the rock-shaft 32. The upper swinging ends of the parallel side lever arm portions 54 are spaced apart and adapted to straddle the said relatively longer yielding lever 53 which is mounted between the said spaced lever arms 54.

The said relatively longer lever arm 53 is formed by preference of a pair of flat stamped metal plates or side flanges 60 which are rigidly secured in fixed parallel relation to each other and spaced apart by means of a sleeve or collar 61 which is interposed between the upper ends of said side flanges, and a transverse pin 62 which extends through said sleeve and through suitable aligned openings in the said side plate flanges 60. The pin 62 is held in place by a cotter-pin 64. The said lever 53 is provided at its lower end with circular openings 65 adapted to encircle the corresponding circular peripheral end portions or shoulders 58 of the said hub or sleeve 56 so as to permit a limited movement of said lever 53 circumferentially of the hub 56 and through said rock-shaft 32 and relatively to the spaced or forked side arm portions 54 of said relatively short lever 52 which is fixed to said rock-shaft. (See Figs. 1, 4 and 5).

A spring-supporting connecting link 66 is attached to and forms a yielding connection between the levers 52 and 53 and comprise a pair of spaced parallel side arms or flanges which are connected at one end of said link by an integral transverse centrally perforated web portion 67. The opposite separate ends of the U-shaped link thus formed are perforated and pivotally connected with the adjacent upper separated ends of the said short lever 52 by means of short headed pivot pins or trunnions 68. A helical compression spring 69 is mounted in the link 66 between the side wall portions thereof, one end of said spring being in abutting engagement with the transverse perforated web 67 of said link, and the opposite end of said spring being in abutting engagement with an upright perforated transverse web or flange portion 70 on the front side of the yielding flexibly connected lever 53. (See Figs. 1 and 4). The upright web or flange portion 70 of said lever 53 is formed by preference by bending opposite short integral flanges or web portions of the side plates 60 of the said relatively long yielding lever together and providing a perforation 71 through the web or flange thus formed. (See Fig. 4).

A headed bolt 72 is mounted in the perforated end web 67 of the said spring-supporting connecting link 66 and extends longitudinally centrally of said link and through the spring 69 and loosely through the pin 71 in the upright web or flange portion 70 of the lever 53. The forward threaded end of the bolt which extends through the perforated web 67 is secured in fixed relation to said web and to the link 66 by means of a milled sleeve nut 73 in threaded engagement with the bolt on the inside of said web and an outer nut 74 which is in threaded engagement with the bolt on the outer side of said transverse end web or flange. The opposite or headed end of said bolt is slidably mounted in the perforation 71 in the upright web or wall portion 70 of the lever 53. It will be readily understood that when said relatively long yielding lever 53 is pressed forward it will tend to compress the spring 69 which is, of course, at a suitable tension, and that as the forward movement of the lever 53 is continued in the operation of moving the ironing shoe toward the ironing roll the relatively short lever 52 will be rocked forward together with the rock-shaft 32 to which said short lever is fixed. The ironing shoe supported on the upright rocking lever 37 will thus be

moved forward into yielding operative engagement with the ironing roll and into ironing engagement with the material to be operated upon as the material is fed over the ironing roll 7 5 and between said roll and ironing shoe.

The ironing shoe supporting and operating rocking shaft and lever mechanism, including the interconnected levers and the connecting link and spring mechanism above described, is 10 thus adapted to be operated by power-driven means and serves to move the ironing shoe forward and to hold it in ironing position in yielding engagement with the material to be operated upon so as to permit material of unequal and 15 irregular thickness to be ironed in an efficient manner and to be subjected to the desired pressure in the ironing operation. To regulate or change and control the pressure of the ironing shoe toward and against the ironing roll it is 20 only necessary to increase the tension of the spring 69 above described by adjusting the nuts 73 and 74 to the required positions upon the bolt 72 which is thus adapted to hold the spring normally at any desired tension to which it 25 may be adjusted.

Suitable power-drive means for operating the ironing roll and ironing shoe is provided and by preference constructed and connected with a source of power and adapted to operate substantially as follows:

A main driving shaft or worm shaft 75 is journaled in suitable bearings in the machine frame or housing and connected with a power-driven shaft 76, which in this instance is the 35 motor shaft of an electric motor 77 or other suitable power-driven shaft or source of power which may be of any ordinary and well-known or suitable form. The said main driving shaft or worm shaft 75 is connected with the motor 40 shaft 76 by preference, by means of a flexible or universal coupling 78 (Fig. 3), which comprises a pair of shouldered collars 79, one of which is fixed to the shaft 75 and the other of which is fixed to the motor shaft 76. And an 45 intermediate shouldered collar or disk 80 is interposed between and in shouldered flexible engagement with said shouldered collar 79 thus forming a flexible connection between the shafts 75 and 76.

50 A worm 81 is fixed to the main driving shaft or worm shaft 75; and a worm wheel 82 is rotatively mounted upon a suitable support and in toothed operative engagement with said worm. For example: The worm wheel 82 is 55 mounted upon and in fixed relation to a hollow shaft or tubular inner hub member 83, one end of which is provided with a toothed clutch member 84 having end clutch shoulders or teeth 85. The inner tubular hub member 83 is 60 encircled by an outer hub member 119 fixed to said worm wheel 82 and a toothed ratchet wheel or ratchet clutch member 86 having peripheral ratchet teeth 87 thereon, is fixed to and adapted to rotate with said worm wheel 82 65 and with said rigidly connected rotative hub members 82 and 119 and with said clutch member 84 on said worm wheel hub.

The worm wheel 82 with its inner supporting hollow shaft or hub member 83 and said outer hub member 119 are rotatively mounted in an inner supporting frame or bracket 88 which is rigidly mounted within the gear chamber 14 of the head or housing 2 already described. Said inner frame or bracket is by preference removably secured in rigid position within said hous-

ing and gear chamber by headed securing screws 89 and 90 anchored in inwardly projecting bosses 91 and 92 on the frame or housing 2. The removable supporting frame or bracket 88 is provided with suitable bearings 93 and 94 in 80 which said worm wheel supporting hollow shaft or inner hub member 83 and a horizontal longitudinally movable shifting clutch-actuating rod or shaft 95 are journaled. The tubular inner hub member or hollow shaft 83 is journaled in the bearing 93, and said longitudinally shiftable clutch actuating rod or shaft 95 is journaled in said bearing 94 and extends through both of said bearings 93 and 94 and through said tubular inner hub member 83 and clutch member 84 on said worm wheel 82, as best shown in Fig. 4; and a spur pinion 96 is mounted on and fixed to a projecting end of said clutch-actuating rod or shaft 95 and provided with end clutch shoulders or teeth 97 located adjacent to and movable into and out of clutching engagement with the clutch shoulders or teeth 85 on said clutch member 84 which is fixed to the worm wheel 82 and to said worm wheel hub 84 and worm wheel supporting hollow shaft 83 as already described. (See Fig. 4.) An end nut or collar 98 on the end of the shifting clutch-actuating rod 95 is adapted to serve as a lock-nut for securely holding the pinion 96 in fixed relation to the said clutch-actuating rod; and a key or spline 98' 100 connects the pinion and movable clutch member 96 with and in adjustable relation to said shaft 95. A helical compression spring 99 which is mounted on the outside of and encircles the bearing 94 is operatively connected with and 105 adapted to shift the longitudinally movable clutch-actuating rod or shaft 95 and the said combined clutch and spur gear member 96 in one direction into clutching engagement with the clutch member 84 on said inner hub member or hollow shaft 83 fixed to said worm wheel 82. An end collar 100 which is fixed to the end of said shiftable clutch-actuating rod or shaft 95 engages the abutting outer end of said spring 110 99, and the inner end of the spring abuts against 120 and encircles the said bearing 94 on the said inner frame 88.

A clutch-actuating rocking lever or yoke 101 (Figs. 1 and 4) is rockingly mounted upon a 125 stationary fulcrum and supporting member 102 and provided with forked yoke-arms 103 which are spaced apart and adapted to extend on opposite sides of the projecting end of said clutch-actuating rod 95 in operative engagement with the end collar 100 fixed to the end of said 130 clutch-actuating rod and engaged by said clutch-actuating compression spring 99 as already described. The said lever 101 is held in operative position upon its supporting fulcrum 102 by means of a headed screw 104, the lever being provided with a suitable recess or socket portion adapted to engage the fulcrum and permit the rocking of the lever thereon in the operation of the clutch.

The ironing roll 7 is operatively connected with the driving mechanism comprising said power-driven main driving shaft 75 and worm wheel mechanism above described. A spur-gear wheel 105 is fixed to the inner projecting end of the axle-shaft 15 of said ironing roll by means of a set screw 106 mounted in the hub of said wheel and held in engagement with said axle by a lock-nut 107 or other suitable securing means; and a key 106' is inserted between said 140 150

- axle-shaft and said hub in an elongated slot in said shaft, so as to permit adjustment wheel lengthwise of the axle-shaft. Said gear wheel 105 is in toothed engagement with the spur gear 5 teeth 108^a on the combined spur pinion and clutch member 96 which is on and shiftable with the longitudinally shiftable clutch-actuating shaft or rod 95 as already suggested. (See Figs. 2 and 4.)
- 10 From the foregoing it will be readily understood that the combined spur pinion and clutch member 96 is always engaged by the spur wheel 105 on the ironing roll axle, and that the worm wheel 82 is in continuous rotation whenever it 15 is connected with the motor and the motor is in operation. It follows that whenever the clutch mechanism comprising said clutch and pinion member 96 and the clutch member 84 fixed to the hub of the worm wheel 82 are in 20 clutching engagement the ironing roll will be kept in rotation, and when said connection is released the ironing roll will remain stationary whenever said clutch mechanism is disengaged.
- Means is provided for effecting the automatic 25 stopping and starting of the rotation of the ironing roll and the operation of the ironing shoe in coordinated relation to each other in such a manner that the automatic operation of the clutch mechanism, including the combined 30 spur pinion and clutch member 96 will be accomplished while the pressure of the ironing shoe against the ironing roll or material to be operated upon is released, and whereby the initial step in the operation of the ironing roll and 35 ironing shoe is enabled to be accomplished manually, the completion of the operation of starting and stopping the ironing roll and the stopping and starting of the movements of the ironing shoe being completed automatically and in predetermined coordinated relation and successive 40 order as follows:
- A hollow shaft section 105¹ which forms an extension of the stationary hollow shaft or tubular member 10 of the axle of the ironing roll 45 is mounted in position to encircle the projecting portion of the axle rod 15 and is by preference fixed to said tubular ironing roll supporting member or hollow shaft 10 within the gear chamber 14; and a bearing or bushing 29 is 50 interposed between said axle shaft and said tubular member 105¹ at the open end of the latter and within the gear chamber and the bearing in which said axle is journaled. A compressible packing ring 107 is also interposed between 55 said axle rod 15 and the tubular member 105¹.
- A spur gear wheel 108 having an elongated tubular hub 109 fixed thereto or forming an integral part thereof is mounted upon and in 60 rotative relation to and encircles the stationary tubular member 105¹ and the rotative axle-shaft 15 within the gear chamber 14. A clutch actuating cam 110 is fixed to or formed integral with the body of said spur-gear wheel 108 in position to slidably engage a cam shoulder 111 on the lever arm 112 of the cam actuating rocking lever or yoke 101 already described. Fixed to the opposite end of the said hub 109 of the spur gear wheel 108 and by preference formed integrally with said hub is an ironing-shoe actuating eccentric 113 which encircles and is rotative with respect to the stationary tubular member 105¹ through which the axle-shaft 15 of the ironing roll axle extends as already described. A connecting rod 114 is provided having a circular eccentric strap 115 on one end thereof and encircling said eccentric 113. The opposite end of said connecting rod 114 is pivotally connected with the upper free or swinging end of the yielding ironing-shoe actuating lever 53 already described, said connecting rod being provided with a suitable opening therein through which the headed end of the connecting pin 64 on said lever 53 extends. A collar 116 which is integral with the pin 62 is interposed between said connecting rod 114 and the lever 53; and a washer 117 is mounted between the headed end of the connecting pin 62 and said connecting rod 114 to form a bearing for the same. A spur gear wheel or pinion 118 is loosely mounted on and in rotative relation to the longitudinally shifting clutch-actuating rod 95 and in toothed engagement with the said spur gear wheel 108 which is in turn loosely mounted on the ironing roll axle and in fixed relation to the shoe-actuating eccentric 95 113 and hub 109 of said gear wheel 118 as already described.
- The connected gear wheels 108 and 118 form a train of gears one of which—namely the gear 100 118—is mounted adjacent to the toothed ratchet wheel 86 on the hub 119 of the power-driven worm wheel 82 already described; and a pawl-supporting plate 120 is fixed to or formed integrally with said gear wheel 118 and adapted to rotate with said spur gear wheel in a position 105 closely adjacent to said toothed ratchet wheel 86 and by preference between the opposed faces of said spur gear wheel and the toothed ratchet wheel. (See Figs. 2, 3, 4, 5 and 7).
- A pawl 121 is pivotally mounted upon said 110 pawl-supporting plate 120 by means of a headed pivot pin 122 which extends through the said pawl and plate and through the perforated outer flanged portion 123 of said plate as best shown in Fig. 3. Said pawl is provided with a pawl 115 tooth 124 thereon which is movable into and out of toothed engagement with the ratchet teeth or shoulders 125 on said toothed ratchet wheel 87; and a pawl-operating lever 126 is interposed between 120 said flange 123 on the plate 120 and said pawl 121 and provided with a laterally extending side flange 127 which overlaps the bottom margin of the pawl 121. Said pawl-operating lever 126 and pawl 121 are thus both pivotally supported upon the same axis formed by the pivot 125 pin 122 anchored to the plate 120 which is fixed to the spur gear wheel 118. A helical spring 128 is secured at one end to the pawl-supporting plate 120 by a headed pin 129, the opposite end of said spring being connected with the pivoted pawl-actuating lever 126 by means of a projecting lug 130 on said lever and provided with a perforation 131 in said lug through which this spring is fastened. The pawl 121 is provided 130 with a projecting end shoulder 132; and the pawl-actuating lever 126 has a similar projecting end shoulder 133 thereon closely adjacent to and by preference in sliding contact with said projecting shoulder 132. The top margins of both 135 of said shoulders are so disposed that they are in the same plane when the toothed pawl 121 is in toothed engagement with the ratchet wheel 87 and the hook 138 of the tripping lever 134 is in engagement with both of said shoulders 132 and 133 for releasing the pawl. The bottom flange 127 on the lever 126 is adapted to engage the adjacent bottom edge of said pawl to effect 140 the raising of the pawl into toothed engagement with the ratchet when the lever 126 is raised with the pawl by the spring 128. (See Fig. 3).

A pawl-actuating and releasing or tripping finger 134 is pivotally mounted upon a horizontal rocking or reciprocating stub shaft 135 journaled in suitable bearings in the inner frame members 136 and 137 directly below and, by preference, substantially in the same vertical plane with the pawl 121 and pawl-actuating lever 126. (See Figs. 3 and 7). Said tripping finger 134 is provided with a hooked end portion 138 at its upper end which is adapted to engage and hold the pawl 121 and pawl-actuating lever 126 in lowered or releasing position out of engagement with the ratchet 87 when the said tripping finger is in initial or normal position and the pawl is in its lowered position, as at the end of a complete revolution of the ratchet concurrently with a half revolution of the gear wheel 108 and eccentric 113. The pawl 121 has sufficient play or lost motion relatively to the pawl-actuating lever 126 to permit the pawl to be held out of engagement with the ratchet wheel 87 by force of gravity when the pawl-actuating lever 126 is in lowered or pawl-releasing position. (See Figs. 3 and 7).

Manually operable means is provided for operating the pawl-releasing or tripping finger 134 to effect the releasing of the pawl and its engagement with the ratchet. For this purpose a rock-shaft 139 is provided, one end of which is connected with a horizontal stub shaft 135 by a transverse connecting pin 140 which is anchored in said stub shaft and extends into transverse slots 141 in the adjacent recessed slotted end of said rock-shaft 139. The outer end of said rock-shaft is journaled in suitable bearings in the machine frame or housing 2 and extends outward to the outside of said housing and is provided with a hand lever or trigger 142 on the outer end of said shaft and in position to be conveniently manually operated in one direction to release and permit the engagement of the toothed pawl 121 with the toothed ratchet wheel 87. A helical spring 143 having one end attached to a supporting frame or bracket member 144 and having the other end of said spring attached to the hooked end 138 of said pawl-tripping and releasing finger 134 serves to return said tripping finger and said lever 142 to initial normal pawl-releasing position as soon as the manually-operable lever or trigger 142 is released by the operator.

The hooked upper end of the tripping finger 134 is thus normally in position to engage and release the pawl 121 and pawl-actuating lever 126 whenever said pawl and lever and their supporting plate 120 complete a revolution after being released by the operation of the hand lever or trigger 142 by the operator.

The gear wheel 118 with which the pawl 126 rotates is by preference of one-half the pitch diameter of the engaged gear wheel 108 which is fixed to the eccentric 113. It follows, of course that for each one-half revolution of the gear wheel 108 with its cam 110 and eccentric 113—the gear wheel 118, the ratchet 87, and the attached pawl-supporting plate 120 and pawl 121 will make a complete revolution. It should also be noted that for each complete revolution of the gear wheel 118 with its attached pawl-supporting plate 120 and the pawl 121—the ironing shoe actuating eccentric 113 which is fixed to and rotative with the gear wheel 108 and the clutch-releasing cam 110 will both rotate with the ironing roll and its axle for one-half of a complete revolution only or until the clutch members 96 and 84 are released by the cam 110 operating the lever 103 to shift the shaft 95 and clutch member 96 to clutch-releasing position, thereby disconnecting the ironing roll from the power-driven worm wheel 82 or source of power. It will be readily understood that when the gear wheel 108 and the connected eccentric 113 are rotated to the position shown in full lines in Fig. 1, the ironing shoe will be moved rearward from and out of contact with the ironing roll and the material to be operated upon, and that the levers 52 and 53 will be held by the eccentric 113 in their rearward or pressure-releasing position as shown in full lines in Fig. 1, until the eccentric 113 is again released and permitted to move a half revolution to the position shown in broken lines in said Fig. 1 by the manual operation of the hand lever or trigger 142 to effect the releasing of the pawl 121 and permit it to engage the toothed ratchet 87 and thereby cause an operation of the ironing shoe toward the roll. Every manual operation of the tripping lever or trigger 142 and the tripping finger 134 will initiate an operation of the ironing shoe either toward or from the ironing roll; and the ironing shoe will be held in and out of engagement with said ironing roll alternately—normally in engagement with the roll when the latter is rotating and out of engagement when the roll is stationary. The automatic releasing of the ironing roll from the power is timed to occur concurrently with the operation of the ironing shoe to its released position away from and out of engagement with the ironing roll and the material to be operated upon.

Each alternate one-half revolution of the gear wheel 108 with the ironing shoe actuating eccentric 113 and clutch-actuating cam 110 causes said cam to engage the cam shoulder 111 on the clutch-actuating yoke lever 103 for shifting the combined pinion and clutch member 96 out of engagement with the clutch member 84 on the worm wheel 82 to effect the releasing of the ironing roll and gear wheel 105 on the ironing roll axle from the source of power concurrently with the operation of releasing the ironing shoe from engagement with the roll and source of power. Since the shoe-actuating eccentric 113 and the clutch-actuating cam 110 are rigidly connected and adapted to rotate together and concurrently with the rotation of the gear wheel 108, and the gear wheel 118 when connected with the worm wheel 82 by the pawl and ratchet mechanism or escapement mechanism above described, makes a complete revolution for each one-half revolution of the gear wheel 108, it follows as a matter of course that the gear wheel 118 with its pawl are automatically released from the worm wheel 82, ratchet wheel 87 and source of power upon the completion of each revolution of the gear wheel 118 and pawl 121. The ironing shoe will be thus released from the power driven worm wheel 82 and source of power and permitted to stop and remain stationary until the escapement mechanism or pawl and ratchet mechanism is again actuated by the manual operation of the hand lever or trigger 142. And this stopping of the ironing shoe will occur whether the ironing shoe is in its released position out of engagement with the ironing roll and material to be operated upon or in operative engagement with the ironing roll and said material. From the foregoing it will be readily understood that the first manual operation of the actuating lever or

trigger 142 and the tripping finger 134 so as to release the pawl 126 and cause said pawl to engage and rotate with the ratchet wheel 86 and worm wheel 82, will effect the starting of the 5 operation of the shoe toward the ironing roll and the starting of the revolution of the ironing roll; and that the automatic tripping of the pawl to release the same from the ratchet at the end of said complete revolution of the connected pawl 10 and ratchet will automatically stop the ironing shoe in its pressure applying position in engagement with the ironing roll without releasing the ironing roll from the source of power. The rotation of the roll is thus continued when the shoe 15 is in engagement with the roll and while pressure is being applied by the ironing shoe, but the rotation of the ironing roll is automatically stopped concurrently with the return operation of the ironing shoe to initial pressure releasing position out of engagement with the ironing roll. 20

Simple and efficient means is also provided for releasing and holding in clutch-releasing position the clutch mechanism for controlling the operation of the ironing roll so that the ironing 25 roll will be disconnected from the source of power and permitted to remain stationary and the ironing shoe may be reciprocated or moved toward and from the ironing roll by the power-driven shoe operating means, as when 30 clothes are to be pressed between the stationary ironing roll and shoe. For example, a manually operable clutch releasing lever 143^a is mounted upon a rocking shaft 144^a which is mounted in a suitable bearing 145 in the machine frame or 35 housing and provided with an eccentric or cam 146 fixed to said shaft and adapted to be rotated into and out of engagement with the side face of the adjacent end surface 147 of the clutch-actuating yoke lever 112 already described. (See 40 Figs. 2, 3 and 5).

The housing 2 is provided with a ventilating opening 148 which opens into the motor casing for admitting air thereto for cooling the motor and for receiving electric wires which are connected with the motor and source of electrical supply and with the heating unit in the ironing shoe. An oil pump 150 which comprises a pump-cylinder 151 fixed to the housing 2 or other suitable supporting means, and having an oil 45 inlet opening 154 leading to the interior of said pump casing at or near the lower end thereof, and a valve-controlled discharge opening 155 leading from the discharge end of the piston chamber. And a piston plunger 156 is mounted 50 in said piston chamber and has a head 157 on the upper extremity of said plunger and located within the path of movement of and adapted to be engaged and operated by a cam or eccentric member 158 which is fixed to and adapted to 55 rotate with the shoe-actuating eccentric 113 already described, for operating the said oil pump plunger and piston. A coil spring 159 within the piston cylinder and in engagement with the piston plunger serves to operate said plunger 60 in the opposite direction from that in which it is operated by the cam or eccentric 158. The oil pump 150 is thus adapted to pump lubricating oil from the bottom of the gear chamber into and over the gearing and other moving parts and 65 bearings in said chamber which is provided with a sufficient quantity of oil for the purpose of lubrication. The lubricating oil is thus kept constantly in circulation and sprayed over the mechanism within the gear casing or housing in streams or jets so that said mechanism is 70

kept constantly and thoroughly lubricated with a minimum quantity of oil which is contained in a gear box in which all of the ironing roll and shoe operating and controlling mechanism is compactly arranged and adapted to operate 80 efficiently.

A supporting leg 160 is provided having a long transverse base or foot 161 which is adapted to rest upon the stationary support or table 3. The base 4 and leg 160 of the machine 85 frame may be attached to the table or other stationary support by any ordinary and suitable securing means such as connecting screws or clamping means—not shown.

The said leg 160 is by preference, fixed to the rigid arm or tubular frame member 33 by means of an annular head 162 in the upper end of said leg. Said annular head or split ring 162 encircles the said rigid tubular member 33 through which the rock-shaft 32 extends. A rigid machine frame is thus provided which is portable and adapted to be firmly or detachably secured on any desired stationary support such for example as a table or a pedestal. 90 95

Briefly stated the normal operation of the machine is as follows:

Assuming that the ironing shoe is in its pressure-releasing position away from and out of contact with the ironing roll and the material to be operated upon, with the ironing roll-controlling power clutch 96 and the ironing-shoe-controlling pawl and ratchet mechanism comprising the ratchet wheel 86 and pawl 126 in power-releasing position, and the shoe-operating eccentric 113 in initial pressure-releasing position, but with the power-driven worm wheel 82 connected with the motor and in continuous rotation (see Figs. 1, 2 and 3), the continuously rotating worm wheel 82 and its driving mechanism may be considered as the source of power 100 with which the ironing roll and ironing shoe are to be connected and from which said roll and shoe are to be released in such a manner as to effect the operations of the ironing roll and ironing shoe in coordinated relation as required. 105 110 115

The material to be operated upon is placed in contact with the periphery of the ironing roll in position to be fed between said roll and the ironing shoe; and the operator operates the trigger 142 or its equivalent, such, for example, as a 120 pedal or knee-operated lever—not shown—either of which may be used with or in lieu of the said hand-lever, all of which is well known by those skilled in the art. The first operation of the 125 manually operable lever or trigger 142 will cause the tripping finger 134, shown in Fig. 3, to release the pawl 126 causing said pawl to engage the toothed ratchet wheel 86, thereby connecting the shoe-operating eccentric 113 with the continuously rotating power-driven worm wheel 82 or source of power. The cam 110 being rigidly connected with the eccentric 113 and loose on the ironing roll axle or axle-shaft 95 and connected with the pawl 126 by the train of gears comprising the gear wheel 108 on which the cam 130 is mounted and the connected gear wheel 118 on which the pawl is mounted by means of the pawl-supporting plate 120 are fixed to said gear wheel 118, it follows that the first one-half revolution of the cam 110 which is in engagement with the clutch-actuating yoke lever 112 will cause the clutch 96 to connect the ironing roll with the rotating worm wheel 82 or source of power and that the concurrent one-half revolution of the eccentric 113 will operate the iron- 135 140 145

ing shoe 31 toward and into engagement with the ironing roll or material to be operated upon concurrently with the automatic connecting of the ironing roll with the worm wheel 82 and 5 source of power. The first complete revolution of the engaged ratchet wheel 86 and pawl 126 and gear wheel 118 will cause said pawl to revolve once around its axis to its initial lower-most position and to be there tripped by the 10 manually operable tripping finger 134 to releasing position out of toothed engagement with the ratchet wheel 86 thereby effecting the automatic releasing of the ironing shoe and shoe-operating eccentric from the source of power 15 and leaving the ironing roll connected with the continuously rotating power-driven worm wheel 82 or source of power. The ironing roll will thus continue to rotate while operatively engaged by the ironing shoe as the ironing proceeds, until 20 the ironing roll is released from the said worm wheel or source of power. The next operation of the hand-lever or trigger 142 by the operator, to effect the return operation of the ironing shoe to pressure-releasing initial or normal position out of engagement with and away from 25 the ironing roll will cause the pawl-tripping finger to trip and release the pawl 126 whereupon said pawl will engage the ratchet wheel 86 and automatically effect the connection of the ironing-shoe operating eccentric 113 and ironing shoe with the continuously rotating worm wheel 82 or source of power, so that the said eccentric and the cam 110 will again rotate one-half of a 30 complete revolution thereby returning the ironing shoe and said eccentric to original initial position. The cam 110 is thus caused to engage the cam shoulder 111 on the clutch-actuating yoke lever 112 and release the clutch member 96 from engagement with the clutch member 85 on 35 the hub of the worm wheel 82 thus disconnecting the ironing roll from the said worm-wheel or source of power immediately following the release of the pressure of the shoe upon the ironing roll. The cycle of operation thus accomplished may be repeated as often as may be desired; and the ironing roll and shoe are thus 40 operated in coordinated relation to each other, each and all of said operations being initiated by a single operation of one manually operable trigger or hand-lever or equivalent manually operable actuating means, and each and all operations thus initiated manually being automatically completed, controlled and coordinated efficiently and with economy in construction and 45 operation.

We claim:

1. In an ironing machine, the combination of a rotative ironing roll, a stationary hollow shaft 60 upon which said roll is rotatably mounted, a rotative axle-shaft connected with said ironing roll and extending through said stationary hollow shaft for rotating said ironing roll, an ironing shoe located adjacent to and movable toward and from said ironing roll, driving mechanism adapted to be connected with a source of power for operating said ironing roll and shoe, a tubular member around one end of said stationary roll-supporting hollow shaft and rotatable thereon, an eccentric mounted upon said tubular member for rotation therewith, means for operatively connecting said eccentric with said ironing shoe for operating the same, a cam 65 mounted on said last-mentioned tubular member for rotation therewith, gear mechanism con-

nected with said axle-shaft, spring-actuated clutch mechanism for connecting said gear mechanism with said first-mentioned driving mechanism, a clutch-actuating lever mounted in engagement with and adapted to be operated by said cam and operatively connected with said spring-actuated clutch mechanism for releasing the same, manually operable means connected with said clutch mechanism for releasing said ironing roll actuating gear mechanism from said first-mentioned driving mechanism, manually engageable means actuated by said driving mechanism for rotating said tubular member, and means operable automatically upon said last mentioned means to stop rotation of said tubular member when said ironing shoe reaches either of its extreme positions. 80 85 90

2. An ironing machine comprising a rotatably supported ironing roll, an ironing shoe movable into and out of operative relation to said roll, a pair of shafts rotatably mounted in laterally spaced parallel relation, a first one of said shafts being operatively connected to said roll for rotating the same, an eccentric rotatably mounted on said first shaft and operatively connected to said shoe for moving the shoe toward and away from the roll, a constantly driven gear rotatably mounted on the second one of said shafts, a geared connection between said gear and said eccentric including a manually engageable clutch on the axis of said second shaft, means operable automatically upon said clutch to stop the rotation of said eccentric when said ironing shoe reaches either of its extreme positions, a geared connection between said constantly driven gear and said first shaft for rotating said roll, said last mentioned connection including a clutch on the axis of said second shaft, and cam means actuated through rotation of said eccentric to operate said roll-controlling clutch and stop rotation of the roll when said shoe is moved away from the roll. 100 105 110 115 120

3. An ironing machine comprising, in combination, a rotatable roll, a shiftable cooperating shoe, a gear casing adjacent to one end of the roll, a pair of spaced parallel shafts rotatably mounted in said casing, a first one of said shafts being operatively and constantly connected to said roll for rotating the roll when said first shaft is rotated, a sleeve rotatably mounted on said first shaft, an eccentric on said sleeve operatively connected to said shoe for moving the shoe toward and away from said roll, a gear fixed to said sleeve, a pinion loosely mounted on the second one of said shafts in mesh with the gear of said sleeve and carrying a clutch element, a constantly driven gear rotatably mounted on said second shaft and carrying a complementary clutch element, automatically operable means acting on one of said clutch elements to open the clutch whenever said shoe reaches one of its extreme positions, intermeshing gears fixed on said first and second shafts, said constantly driven gear having a clutch element thereon engageable with the gear on said second shaft for rotating the same, said second shaft being longitudinally shiftable to disengage its gear from its associated clutch element, and cam means operated by said sleeve in its rotation to shift said second shaft and stop said roll when the shoe is moved away from said roll. 125 130 135 140 145

4. An ironing machine comprising a rotatably supported ironing roll, an ironing shoe mova- 150

ble into and out of operative relation to said roll, a pair of shafts rotatably mounted in laterally spaced parallel relation, an eccentric rotatably mounted on a first one of said shafts 5 and operatively connected to said shoe for moving the shoe toward and away from the roll, a constantly driven gear rotatably mounted on the second one of said shafts, a geared connection between said constantly driven gear and 10 said eccentric including a manually engageable clutch, means operable automatically upon said clutch to stop the rotation of said eccentric when said ironing shoe reaches either of its extreme positions, a geared connection between 15 said constantly driven gear and said roll for

rotating the roll, said last mentioned connection including a roll-controlling clutch having an internal gear on said second shaft rotated thereon with said constantly driven gear, and a pinion fixed to said second shaft and engageable with said internal gear by longitudinal shifting of said second shaft, and cam means actuated through rotation of said eccentric to shift said second shaft longitudinally to operate said roll-controlling clutch and stop rotation of the roll when said shoe is moved away from the roll. 80 85 90
